UNITED STATES PATENT OFFICE.

DAVID B. OLIVER, OF ALLEGHENY, PENNSYLVANIA.

ROLLING-MILL.

SPECIFICATION forming part of Letters Patent No. 249,662, dated November 15, 1881.

Application filed June 23, 1881. (No model.)

To all whom it may concern:

Be it known that I, DAVID B. OLIVER, of Allegheny, in the county of Allegheny and State of Pennsylvania, have invented a new 5 and useful Improvement in Rolling-Mills; and I do hereby declare the following to be a full, clear, and exact description thereof.

My invention relates to improvements in mills for rolling skelp and band iron. One 10 form of mill for this purpose consists of a train of non-reversing two-high rolls, in which the iron is drawn out by passing through in one direction, and hence requires to be transferred after each pass from the delivery side to the 15 feed side, in order to be again entered into the rolls. This transfer has heretofore been made by the workmen on the delivery side taking hold of the piece with their tongs and pushing it back under the rolls. The workman on the 20 feed side then takes hold of the end and inserts it into the rolls. The pile from which the skelp or band is made weighs from fifty to four hundred pounds, according to the size of the skelp required, and at the final grooved 25 pass generally obtains a length of sixty feet or more. After this pass it is so long and thin that it is very difficult to push through under the rolls to the feed side for the finishing pass; but the chief difficulty is to start it as it lies 30 on the floor. To do this two men take hold of it at the back end and push, and two others take hold of it at the center and pull. Once started it slides over the polished floor-plates with comparative ease; but it is very difficult 35 to start, as it is not only heavy and unwieldy, but, being very thin, buckles or bends up in the middle, and requires to be again flattened. The operation is consequently laborious to the workman, and the delay causes a loss of heat, 40 and thereby reduces the production and increases the cost of manufacture.

My invention relates to mechanism for transferring the piece from the delivery to the feed side of the finishing-rolls, whereby I reduce 45 the labor and increase the product.

To enable others skilled in the art to make and use my invention, I will now describe it by reference to the accompanying drawings, in which—

50 Figure 1 is a side elevation, showing my improvement. Fig. 2 is a plan view, and Fig. 3 a vertical longitudinal section.

Like letters of reference indicate like parts in each.

The finishing-rolls *a* and *a'* are mounted in 55 housings *b* of the usual construction. Mounted in the bed-plate *c* or otherwise is a roller, *d*, which is driven by power from one of the rolls by means of a belt, *e*, and pulley *f*. Pivoted to a suitable bearing, *g*, is a lever, *h*, carrying 60 a loose roller, *i*, on one end, an adjustable counter-weight, *j*, on the other end, and with a handle or arm, *k*, extending from its side, preferably at right angles to it, for operating it and bringing the roller *i* down upon the 65 roller *d*. Extending from the roller *d*, under and to the other side of the rolls *a* *a'*, is a trough, *l*, and on the delivery side of the rolls is a delivery-trough, *m*, which extends preferably beyond the rollers *d* and *i*. 70

The operation is as follows: The piece, after being delivered from the last grooved pass of the train, lies on the floor, a long, thin, wide band of hot iron, with its end at one side of the rollers *d* *i*. It is seized by the workman 75 and dragged sidewise onto the roller *d*, which is an easy operation. The workman then takes hold of the handle *k* and draws the roller *i* down upon the piece. This causes the piece to be fed back through the trough *l* under the 80 rolls *a* *a'*. When its end passes beyond the end of the trough the workman seizes it with his tongs and turns it backward and inserts it into the rolls *a* *a'*, as shown by dotted lines in Fig. 3, which then give it the finishing pass. 85 The end of the trough *l* is turned up slightly at *l'*, to give an upward direction to the end of the piece, so that it may be more easily caught by the workman. When the roller *i* is brought down on the piece the weight *j* slides inward 90 along the lever *h*, and when the roller is thrown up the weight, sliding back to place, holds the rollers apart. The use of my improvement not only saves time and labor, but increases the 95 product of the mill.

If preferred, the upper roller, *i*, may be driven by power and the lower roller, *d*, turn loosely by friction; or power may be applied to drive both rollers. It is necessary that a power-driven roller be present to move the piece, and 100 that a pressure-roller be used to hold the piece against the actuating-roller, in order that the friction of the latter upon the piece may be sufficient to move it.

What I claim as my invention, and desire to secure by Letters Patent, is—

1. The combination, with a pair of skelp or band iron rolls, of a pair of transfer-rollers arranged on the delivery side of the finishing-rolls and adapted to return the skelp or band to the feed side of the work-rolls, one of said transfer-rollers being power-driven and one being a movable pressure-roller, substantially as and for the purpose specified.
2. The combination, with a pair of skelp or band iron rolls, of a receiving-trough arranged on the delivery side of said rolls, a pair of transfer-rollers arranged near the delivery end 15 of the receiving-trough, and a return-trough

arranged below the work-rolls and extending from the transfer-rollers to the feed side or front of the work-rolls, substantially as and for the purpose specified.

3. The combination, with the skelp or band iron rolls and the transfer-rollers, of a return-trough having its delivery end turned up, substantially as and for the purpose specified.

In testimony whereof I have hereunto set my hand.

DAVID B. OLIVER.
